UNITED STATES PATENT OFFICE

2,008,537

ELECTRIC FURNACE REGULATOR SYSTEM

Frederick E. Ackley, Schenectady, N. Y., assignor
to General Electric Company, a corporation of
New York

Application October 26, 1932, Serial No. 639,625

6 Claims. (Cl. 13—13)

My invention relates to electric furnace regulator systems, more particularly to electric arc furnace regulator systems, and has for its object the provision of simple and reliable means for adjusting the electrodes so as to maintain a predetermined current in the electrode circuit.

More particularly it is an object of my invention to provide control means for the electrode adjusting means whereby the electrode is adjusted quickly in response to changes in the electrode current and furthermore without over adjustment or hunting action. The rate of adjustment is made dependent upon the amount of the adjustment to be made in such manner that the electrode is adjusted rapidly for relatively large changes in position, the rate of adjustment decreasing as the electrode approaches its final position.

In carrying out my invention, I provide a pair of spaced contacts together with a cooperating contact member provided with projections which is rotated at a predetermined speed between the contacts. I also provide means for moving one or the other of the two contacts into engagement with the projections in response to the current in the electrode circuit and in dependence upon the direction of the necessary adjustment whereby means are operated to control the electrode adjusting means. The length of time that the contact is in engagement with any one projection is dependent upon the amount of the correction. For a small adjustment the contact is moved merely enough to just make contact with these projections, the contact being quickly broken, whereas for a larger adjustment the contact is moved farther so that it rides over the projection and maintains contact therewith for a longer interval. I have also provided a second pair of contacts between which is a rotating contact disc, these contacts being adjusted to engage the disc upon a current change of a predetermined greater magnitude and thereby cause the motor to operate at a higher speed for a quick rough adjustment.

For a more complete understanding of my invention reference should be had to the accompanying drawing, the single figure of which shows in diagrammatic form an arc furnace regulator system embodying my invention.

Referring to the drawing, I have shown my invention in one form as applied to an arc furnace 10 comprising a suitable crucible 11 for a metallic charge 12 and suitable electrodes 13, 14 and 15 extending into the crucible into arced relation with the charge. While the furnace is thus

shown as a three-phase one it will be understood that my invention is also applicable to a single phase furnace. The electrodes are each adjustable in a vertical direction to vary the length of the arc in any suitable manner. This adjusting means is shown diagrammatically for the electrode 15 only and comprises a suitable reversible electric motor 16 shown as a direct motor provided with a shunt field winding 17, which motor is connected to rotate a fixed gearwheel 18 having its bore threaded to receive a screw rod 19 attached to the electrode 15.

My invention relates in particular to a current responsive control system for the electrode motor 16. It will be understood, of course, that while only one control system for this one electrode is shown a similar control system will be provided as desired for each of the electrodes 13 and 14.

The current responsive control system for the electrode motor 16 comprises a contact device 20 provided with two pairs of spaced contacts 21, 22 and 21a, 22a, shown as spring contact arms which are mounted in insulated relation to each other on a suitable supporting member 24. This member 24 is mounted on a pivot shaft 25 and is connected to an electric torque motor 26 for movement on its pivot. The torque motor 26 is connected to be energized from a current transformer 27 in the circuit of the electrode 15. The torque motor is biased in one direction by means of the spring 28, the torque applied by the motor being in opposition to the spring. An adjustable rheostat 29 is connected across the current transformer 27 for adjusting the current response of the torque motor. Also a suitable fluid damping device 30 is connected to the torque motor.

A rotating contact member shown as a starwheel 31 is mounted between the pair of contact arms 21, 22, it being secured to a shaft 32 driven by a suitable synchronous driving motor 33 which is connected through a transformer 34 to the source of supply 35 for the furnace. The shaft 32 is parallel with the pivot shaft 25 although this relation has been modified somewhat in the drawing for purposes of clarity. During the operation of the furnace the starwheel 31 is rotated between the pair of contacts 21, 22 at a substantially constant speed. The distance between the contacts is somewhat greater than the diameter of the starwheel so that when the contacts are in a central position, corresponding to the desired current in the circuit, the starwheel is free to rotate without touching either contact.

In the operation of the system, a decrease in

current in the circuit of the electrode 15 below a predetermined value to be maintained, for which the torque motor 26 is adjusted by means of the resistance 29, results in a decrease in the 5 torque of the motor 26 whereby the contacts are turned about the pivot 25 in a clockwise direction, as viewed in the drawing, by means of the spring 28. This brings the contact 21 into engagement with the starwheel whereby a circuit is closed 10 from one side of a suitable direct current supply source 36 through the conductor 37, the switches 38, 39 and 40 which are normally closed, the conductor 41, a collector ring 42 and thence through the shaft 32 or by means of a suitable conductor 15 to the starwheel 31. From the starwheel the circuit continues through the contact 21, the conductor 43, an operating coil 44, and conductor 45 back to the opposite side of the supply source 36. The operating coil 44 picks up a switch 46 in the 20 circuit of the electrode motor 16 thus closing a circuit to start the motor in the direction to lower the electrode. The closing of the switch 46 at the same time opens a normally closed switch 47 which is mechanically interlocked with the switch 25 46. The circuit of the motor 16 may be traced from one side of the supply source 36 through the conductor 48, the resistance 49, the resistance 50, the switch 46, conductor 51, the series field 52 of the motor, the armature of the motor, conductor 53, a normally closed switch 54, the resistance 55, and conductor 45 back to the opposite 30 side of the supply source. It will be understood that the normally closed switches 47 and 54 are suitably held in their closed positions, shown 35 in the drawing, as by the friction in the switch parts or by means of suitable springs (not shown).

It will be observed that if the change in the electrode current to be corrected for is relatively 40 small, then the torque motor will give the contact 21 a relatively small movement so as to bring the contact into position to perhaps be barely touched by each projection of the starwheel as it moves past. In such case the motor 45 operates only a relatively small part of the time, that is, while the contact is actually engaged by the starwheel to close the circuit, the motor being stopped quickly by dynamic braking when the control circuit is broken by disengagement of the 50 contact. The dynamic braking circuit for the motor 16 may be traced from one side of the armature through the conductor 51, switch 47, a resistance 55, switch 54, and the conductor 53 back to the other side of the armature. The particular 55 dynamic braking switch 47 or 54 which is open when the motor is in operation is immediately closed, when the control circuit is opened, by its respective operating coil 56 or 57. These coils are connected in parallel across the motor 60 armature, and hence are energized by the counter-electromotive force of the motor to close the switch 47 or 54 which is open when the control circuit is opened.

In case a relatively great change in electrode 65 current is to be corrected for, then the torque motor moves contact 21 a corresponding great distance so that it will be engaged earlier by each projection of the starwheel, that is, before the point of the projection reaches it. It will be observed that each projection of the starwheel is shaped like a saw tooth, it being wider at the base. After engagement, the contact rides up and over the end of the projection to the other side by 70 reason of the resiliency of its spring arm support thus maintaining the control circuit closed 75

for a longer period of time with consequent increased period of operation of the electrode motor. As the current increases due to the corrective action, the torque motor moves the contact 21 away from the starwheel and consequently the periods of operation of the motor decrease with consequent slowing down in the rate at which the electrode is lowered. Finally when the predetermined current has been reestablished in the electrode circuit, the contact 21 will have been moved 10 to a position where it is no longer engaged by the starwheel and the electrode motor consequently remains at rest. It will be observed that the control system causes the motor to operate for a greater part of the time upon relatively great current changes thereby giving a rapid adjustment, and for a smaller part of the time upon small current changes thereby giving a slow adjustment. 15

In case the current in the electrode circuit increases to a value greater than the predetermined value, the torque motor 26 moves the contact 22 into engagement with the starwheel whereby a circuit is closed for the operating coil 58, this circuit leading from the starwheel through the 25 contact 22, conductor 59, the coil and conductor 45 to the other side of the supply source 36. This closes the switch 60 in the armature circuit of the electrode motor 16 whereby the armature is connected to the supply source 36 for opposite 30 rotation, the braking switch 54 being at the same time opened since it is interlocked with the switch 60. The circuit of the motor now leads through the conductor 48, resistance 49, switch 60, conductor 53, the armature of the motor, the series 35 field 52, conductor 51, switch 47 and conductor 45 back to the supply source 36. This produces rotation of the electrode motor to raise the electrode, the motor being operated for short intervals of gradually decreasing duration, and 40 stopped by dynamic braking, until the electrode current has been re-established as will be understood from the previous description.

It will be observed that when the electrode is being raised the resistance 49 is included in the 45 armature circuit of the motor 16 but not the resistance 50 whereas both resistances are included in the circuit when the electrode is lowered. This provides for the increased torque required to raise the electrode and also tends to cause the motor 50 to operate at a lower speed when lowering the electrode.

Mounted on the shaft 32 between the pair of contacts 21a, 22a is a conducting disc 61. This disc is connected to the same circuit as the starwheel 31. Upon a relatively great or maximum change in electrode current one or the other of these contacts is moved into engagement with the disc 61 whereby a circuit is closed for an operating coil 62 which opens a switch 63 and thereby opens a shunt circuit connecting the resistance 64 across the armature of the electrode motor. This auxiliary control means operates to continuously maintain the switch 63 open and thus provides for increased speed of operation of the electrode motor to give a still more rapid initial adjustment under the control of the starwheel until contact with the disc 61 is broken, after which the starwheel completes the adjustment as previously described. 65

I have also provided a system of connections for preventing operation of the electrode motor in case of a relatively great decrease in the current in one electrode such as might be caused, for example, by the throwing of a shovelful of lime 70 75

underneath one of the electrodes. The high resistance of the lime results in a decrease in the current in the electrode in contact therewith and therefore a decrease in the current in the other 5 two electrodes. It is a characteristic of an arc however that, assuming a given length of arc, the voltage across the arc varies inversely with the current through it. Therefore a decrease in the current through the other two arcs results in an 10 increase in their voltage, and since a fixed voltage only is available from the source of supply 35, this increase in voltage across two of the arcs results in a lower available voltage across the lime, that is, between that electrode and the bath. 15 If no protection were provided for this contingency the automatic regulators would operate to lower the electrodes.

To provide against this contingency I provide suitable means responsive to this decreased voltage 20 from one electrode to the bath for preventing the automatic regulators from lowering the electrodes. Specifically I provide the three undervoltage relay switches 38, 39 and 40 which are normally held closed by operating coils 65, 66 and 25 67 connected respectively across the arcs to the electrodes 13, 14 and 15. As shown, one common connection for the three coils is made through a conductor 68 connected to the charge 12 which forms a neutral point of the three-phase circuit. 30 Therefore, in case the voltage between any one electrode and the bath decreases to value below a predetermined minimum, the corresponding undervoltage relay drops out and opens its switch, thus preventing closure of any one of the control 35 circuits for the three electrode motors. It will be understood that the conductor 41 leads, through the conductors 69 and 70, to the control circuits of the other two electrodes.

This means for preventing lowering of the electrodes is described and claimed in a copending application of Numan R. Stansel, S. No. 651,340, filed January 12, 1933, and assigned to the same assignee as this invention.

The torque motor 26 may be of any suitable 45 type and may consist, for example, of two coils one of which is mounted for rotation and is connected to the support 24, these two coils being inductively related. A dephased current for one coil is provided by a resistance 71 and a condenser 72 in its circuit. Preferably adjustable stops 73 and 74 are provided for limiting the 50 movement of the contact device in each direction and prevent damage to the device in the event of current surges.

55 While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:

65 1. An electric furnace regulator system, comprising in combination with an electrode, adjusting means for said electrode, means continuously driven for effecting intermittent operation of said electrode adjusting means to raise or to 70 lower said electrode, means for varying the duration of the time of operation of said electrode adjusting means, means responsive to the current in said electrode for operating said duration adjusting means, and auxiliary means responsive to a predetermined maximum change in said cur-

rent for controlling said electrode adjusting means.

2. An electric furnace regulator system comprising in combination with an electrode a motor for raising and lowering said electrode, switching means for intermittently closing the circuit of said motor for variable periods of time, means for continuously operating said switching means, means responsive to variations in the current in said electrode for operating said switching means to initiate closure of said motor circuit for operation to raise or to lower said electrode for periods of time dependent upon the magnitude of said current variations and auxiliary means responsive to current variations of 15 a predetermined maximum magnitude for controlling said motor.

3. An electric furnace regulator system comprising the combination with an electrode, a motor for raising and lowering said electrode, circuits for said motor including a pair of movably mounted spaced spring contacts, a starwheel mounted for rotation between said contacts, means for rotating said starwheel, means responsive to the current in said electrode for moving 20 one or the other of said contacts into engagement with said starwheel to close the circuit of said motor for operation to raise or to lower said electrode, a second pair of spaced contacts mounted for movement with said first pair, a disc mounted for rotation with said starwheel between said second pair of contacts, said second pair of contacts being arranged to engage said first contacts upon the occurrence of greater current variations, and means controlled by said 25 second pair of contacts for continuously controlling said motor to give a more rapid movement of said electrode.

4. An electric furnace regulator system comprising in combination with an electrode, a motor for raising and lowering said electrode, selective switching means for intermittently closing the circuit of said motor for variable periods of time and for operation to raise or to lower said electrode, means for continuously operating said 40 switching means, means responsive to a decrease in the current in said electrode below a predetermined value for operating said switching means to close the circuit of said motor for operation to lower said electrode, means responsive to an increase in the current in said electrode above a predetermined value for operating said 45 switching means to close the circuit of said motor for operation to raise said electrode, said switching means being operated to maintain the 50 circuit of said motor closed for periods of time dependent upon the magnitude of said current variations, and auxiliary means responsive to a decrease in current below said predetermined minimum value or an increase in current above 55 said predetermined maximum value for establishing a continuous contact to control said motor for movement of said electrode at an increased rate.

5. An electric furnace regulator system comprising in combination with an electrode, a motor for raising and lowering said electrode, selective switching means for intermittently closing the circuit of said motor for variable periods of time and for operation to raise or to lower said 70 electrode including an intermittent contact member, a second contact member cooperating with said intermittent contact member, said intermittent contact member being mounted for movement to make intermittent contact with 75

- said second contact member, means for driving said intermittent contact member, means responsive to a decrease in the current in said electrode below a predetermined value for operating 5 said second contact member to close the circuit of said motor for operation to lower said electrode, means responsive to an increase in the current of said electrode above a predetermined value for operating said second contact member 10 to close the circuit of said motor for operation to raise said electrode, means for establishing a dynamic braking circuit for said motor when its circuit is opened under the control of said intermittent contact member, and an auxiliary 15 means responsive to a decrease in current below said predetermined minimum value or an increase in current above said predetermined maximum value for establishing a continuous contact to control said motor for movement of said electrode at an increased rate. 20
6. An electric furnace regulator system comprising in combination with an electrode, a motor for raising and lowering said electrode, circuits for controlling the direction of rotation of

said motor including a pair of spaced contacts mounted for movement in one or the other of two directions, a contact member mounted for rotation between said spaced contacts, means for rotating said contact member, said contact member being provided with means arranged to intermittently engage one or the other of said spaced contacts when said contact member is rotated, means responsive to the current in said electrode for moving said contacts in one direction or the other to bring one or the other of said contacts into engagement with said intermittent contact member, an auxiliary pair of spaced contacts mounted for movement with said first pair of spaced contacts, an auxiliary rotatable contact member mounted for rotation with said first rotatable contact member and arranged to be engaged by said auxiliary pair of contacts to maintain a continuous contact to control said motor for increased rate of movement of said electrode, 20 and means for dynamically braking said motor when its circuit is opened under the control of said first pair of spaced contacts.

FREDERICK E. ACKLEY.
